LAUNDRY PACKAGE

Leland R. Morse, Chicago, Ill.

Application November 10, 1934, Serial No. 752,407

1 Claim. (Cl. 229—87)

This invention relates to improvement in laundry packages, and more particularly to a novel manner and means for packaging freshly laundered shirts.

It is an object of this invention to provide a simple, efficient and inexpensive package for use by laundries to preserve the shape and freshness of a shirt during transportation and after delivery to the customer without the necessity of employing pins or like securing means attached to the body of the shirt.

With these and other objects in view, reference is made to the accompanying sheet of drawings which illustrates a preferred embodiment of this invention with the understanding that detail changes may be made without departing from the scope thereof.

In the drawing:

Figure 1 is a view in front elevation of a freshly laundered shirt packaged in accordance with this invention.

Figure 2 is a view in rear elevation of Figure 1.

Figure 3 is a top plan view of Figure 1.

Figure 4 is a view in front elevation of an expanded strip of flexible material employed in carrying out this invention.

For many years, many different means have been adopted by commercial laundries for folding a shirt just laundered and wrapping it in a package that will protect it from being soiled and otherwise preserve its freshness during transportation to the customer and after receipt by the customer until it becomes desirable to wear it.

In the embodiment of this invention illustrated, a freshly laundered shirt is folded over an elongated rectangular board 1, such as card board or other light and inexpensive material of sufficient rigidity to hold its shape during ordinary handling, with the top of the board adjacent and at the rear of the top of the collar or neck band 2, the sides 3 and 4 are symmetrically folded over the longer opposite sides of the board 1 to embrace the sleeves and overlap each other at the back of the board, and the tail 5 of the shirt then folded up over the lower end of the board, as has been the custom in one type of shirt package.

In this type of package, the collar or neck band 2 lies entirely upon the front surface of the board 1 and stands up from the body of the shirt with the buttonholed free ends secured by the insertion of a collar button 6 of bone or other inexpensive material with the center of the front of the shirt lying over the longitudinal center line

of the board 1. As the sides of the shirt are symmetrically folded over the longer edges of the board, the folds of the shoulders 7 slope downward on each side of the collar or neck band so that the edges of the folded shoulders meet at a point 8 upon the back of the board about half-way between the top of the neck collar band 2 and the collar button 6.

Heretofore, strips of thin flexible fibrous material, such as paper, of various widths have been employed to wrap about the shirt so folded and the over-lapped ends secured at the back in any desired manner. However, it is necessary to secure the top of the overlapped shoulder portions by a pin or other means for securing one portion 15 to the other to prevent the tops of these folded and over-lapped portions from falling away from the board 1 over the top of the wrapper as the top edge of the wrapper engages the collar button 6 of the neck or collar band 2 on the front of 20 the shirt package which prevents the wrapper from embracing the meeting point of the folded shoulder 7. Also, in such a package, the board is bowed outward along its longitudinal center to draw the fabric of the front of the shirt taut 25 thereover to prevent wrinkles, and the tops of the folded-over shoulder portions, unless pinned or otherwise secured to each other fall outward over the top of the wrapper.

In accordance with this invention, the top edge 30 of the wrapping strip 9 of thin paper or other material is provided with a cut-out portion 10, approximately in the center of the edge, adapted to receive the neck or collar band 2 of the shirt so that when folded over with the bottom of the 35 recess in engagement with the collar button 6, the top edges 11 and 12 departing from each side of the recess 10 will pass over the meeting point 8 of the shoulder portions 7 and the body of the over-lapped wrapper will embrace completely the 40 over-lapped portions of the shoulders, and when the ends 13 and 14 of the wrapping strip are secured to each other at the back by a sticker 15 or in any desired manner, the over-lapped meeting of the shoulder portions being covered by the 45 wrapper will be held in place without the necessity of any additional securing means. The wrapping strip 9 may be any width desired.

It is therefore obvious that by the above described means, a shirt may be packaged simply 50 and efficiently at less cost and with fewer operations than heretofore, and at the same time preserve the freshness of a laundered shirt.

What I claim is:

A laundry package of the character described, 55

comprising a semi-flexible oblong board about which a shirt is adapted to be folded with the sleeve and shoulder portions thereof overlapping at the rear of said board, a thin flexible wrapping strip separate from the board and folded around the sides of the folded shirt, said wrapping strip being provided at its upper edge with a notch to accommodate the neck band of the shirt, means

for securing the free ends of the wrapping strip together to form a tubular container of a length sufficient only to hold the overlapped sleeve and shoulder portions of the shirt in folded condition independently of pins or the like, and allowing 5 portions of said shirt to project above and below said tubular container.

LELAND R. MORSE.
